GAME BOARD

Erwin Knoll and Lawrence M. Stern, Washington, D.C.,
assignors to Washington Educational Enterprise Pro-
ductions (WEEP), Washington, D.C., a partnership

Filed June 26, 1964, Ser. No. 80,602

Term of patent 3½ years

(Cl. D34—5)

Fig. 2

FIGURE 1 is a top plan view of the upper section of a game board, showing our new design; and,

FIGURE 2 is a top plan view of the lower section of the game board shown in FIGURE 1.

The parts shown in FIGURES 1 and 2 are joined together in proper relationship to form the playing surface of the game board. In FIGURES 1 and 2, the fragmentary indications of colors are continuous throughout the several areas, respectively, and the dominant features of the design are shown in full lines.

The back or reverse side thereof is plain, unornamented and is conventional, and the game board is of conventional thickness.

We claim:

The ornamental design for a game board, as shown and described.
